The ornamental design for a lancing device, as shown and described.

DESCRIPTION

FIG. 1 is a perspective view of the lancing device that illustrates the novel design;

FIG. 2 is a top view of the lancing device of FIG. 1;

FIG. 3 is a left side view of the lancing device of FIG. 1;

FIG. 4 is a bottom view of the lancing device of FIG. 1;

FIG. 5 is a right side view of the lancing device of FIG. 1;

FIG. 6 is a front view of the lancing device of FIG. 1; and,

FIG. 7 is a rear view of the lancing device of FIG. 1.
